DESIGN FOR A COMBINED ENGAGEMENT
RING AND WEDDING RING

Martin E. Untermeyer, South Orange, N. J.

Application November 9, 1946, Serial No. 134,643

Term of patent 7 years

(Cl. D45—10)

To all whom it may concern:

Be it known that I, Martin E. Untermeyer, a citizen of the United States, residing at 73 Glenview Road, South Orange, in the county of Essex and State of New Jersey, have invented a new, original, and ornamental Design for a Combined Engagement Ring and Wedding Ring, of which the following is a specification, reference being had to the accompanying drawing, forming part thereof.

Fig. 1 is an edge elevational view of a combined engagement ring and wedding ring showing my new design, disclosing the wedding ring side;

Fig. 2 is a side view of the combined engagement ring and wedding ring;

Fig. 3 is a top plan view thereof; and

Fig. 4 is an edge elevational view similar to Fig. 1 disclosing the engagement ring side of the combined engagement ring and wedding ring.

I claim:

The ornamental design for a combined engagement ring and wedding ring, as shown.

MARTIN E. UNTERMEYER.
